COMBINED MICROPHONE AND BASE
THEREFOR

Joseph B. Federico, New Baltimore, Mich., and
Maurice M. Palo, Conneaut, Ohio, assignors to
The Astatic Corporation, Conneaut, Ohio, a
corporation of Ohio

Application October 5, 1948, Serial No. 148,976

Term of patent 7 years

(Cl. D26—14)

To all whom it may concern:

Be it known that we, Joseph B. Federico and Maurice M. Palo, citizens of the United States, residing at New Baltimore, in the county of Macomb and State of Michigan, and Conneaut, in the county of Ashtabula and State of Ohio, respectively, have invented a new, original, and ornamental Design for a Combined Microphone and Base Therefor, of which the following is a specification, reference being had to the accompanying drawing, forming part hereof.

In the drawing:

Figures 1, 2 and 3 are top plan, front elevational and side elevational views, respectively, of a combined microphone and base therefor, showing our new design;

Figure 4 is a perspective view of the microphone housing of our new design; and

Figure 5 is a perspective view of the base member of our new design.

We claim:

The ornamental design for a combined microphone and base therefor, as shown.

JOSEPH B. FEDERICO.
MAURICE M. PALO.
